(57) **CLAIM**

The ornamental design for a computer mice, as shown and described.

DESCRIPTION

FIG. 1 is a top perspective view of a computer mice, showing my new design;

FIG. 2 is a bottom perspective view thereof;

FIG. 3 is a front elevation view thereof, the rear elevation view being a mirror image of FIG. 3;

FIG. 4 is a left side elevation view thereof;

FIG. 5 is a right side elevation view thereof;

FIG. 6 is a top plan view thereof;

FIG. 7 is a bottom plan view thereof;

FIG. 8 is a partial enlarged view of FIG. 1;

FIG. 9 is a partial enlarged view of FIG. 2;

FIG. 10 is a partial enlarged view of FIG. 2;

FIG. 11 is a partial enlarged view of FIG. 2;

FIG. 12 is a partial enlarged view of FIG. 3; and,

FIG. 13 is a partial enlarged view of FIG. 4.

The broken lines in the figures depict portions of the computer mice that form no part of the claimed design.
